UNITED STATES PATENT OFFICE.

W. EDWIN ULMER, OF BOSTON, MASSACHUSETTS.

DESIGN FOR A CREST FOR DIALS.

SPECIFICATION forming part of Design No. 36,938, dated May 31, 1904.

Application filed May 31, 1902. Serial No. 109,803. Term of patent 14 years.

To all whom it may concern:

Be it known that I, W. EDWIN ULMER, a citizen of the United States, and a resident of Boston, in the county of Suffolk and Commonwealth of Massachusetts, have invented a new, original, and ornamental Design for a Crest for Dials, of which the following is a specification, reference being had to the accompanying drawings, forming part thereof.

Figure 1 is a front elevation of the crest

embodying my design. Fig. 2 is a side elevation of same.

What I claim as new, and desire to secure by Letters Patent, is—

The ornamental design for a crest for dials, 15 as shown.

W. EDWIN ULMER.
